UNITED STATES PATENT OFFICE.

KENNETH J. UNWIN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LATERALLY-MOVABLE DETECTOR IN LOOM TRANSFERRER.

Application filed December 27, 1926. Serial No. 157,077.

This invention relates to weft detectors of the type mounted in regularly moving trans- 50 ferrer arms and it is the principal object of the invention to provide a detector movable laterally with respect to its indicating side slipping movement.

In detectors of the type set forth in patent to Ryon No. 1,372,316 the detector is moved toward the bobbin from above while the lay 10 is advancing toward front center. It is found that detectors of this type are in contact with the weft a sufficient length of time during the movement of the lay to cause abrasion of the yarn. It is an important 15 object of my present invention to provide a detector supported by but loosely fitted to the transferrer and held in a predetermined position by a light resilient device which will yield to permit the detector to 20 move with the bobbin as the lay advances. The supporting pivot of the detector preferably extends through a slot in said detector of a width substantially equal to the diameter of the pivot but of a greater length.

It is a more particular object of my invention to provide the detector with a concave weft engaging surface to facilitate the movement with the weft and to insure movement of the detector against the light resili- 25 ent device.

With these and other objects which will appear as the description proceeds, my invention relates to the arrangements and combinations of parts hereinafter set forth, 30 and more particularly pointed out in the claims.

In the accompanying drawings, wherein a convenient embodiment of my invention is shown,

Fig. 1 is a vertical central section through that part of the transferrer which lies over the bobbin when the shuttle is on the magazine side of the loom, the detector being shown in non-indicating position and in contact with an abundant supply of weft,

Fig. 2 is a view similar to Fig. 1 with the detector having been moved to indicating position by contact with an exhausted supply of weft,

Fig. 3 is a vertical section on line 3—3 of Fig. 1,

Fig. 4 is a horizontal section on line 4—4 of Fig. 1, and

Fig. 5 is an enlarged detail section on line 5—5 of Fig. 3.

Referring to the drawings, a trans- 55 ferrer arm 10 has a bobbin butt engaging heel 11 and a yarn engaging tip 12 and is also provided with a pair of spaced parallel vertical walls 13 between which extend a web 14. A plunger 15 is mounted for sliding horizontal movement in a portion of the trans- 60 ferrer arm and passes through said web 14. The plunger is surrounded in part by a compression spring 16 which lies between 65 the head of the plunger and the web and tends normally to move said plunger to the right from the position shown in Fig. 1.

A latch 17 pivoted as at 18 to the trans- 70 ferrer arm has a hook 19 to engage a notch 20 of the plunger and holds the latter in the position shown in Fig. 1. A torsion spring 21 surrounds the stud 18 and has one end thereof in contact with the trans- 75 ferrer arm as at 22 and the other end in contact with the latch as at 23, said torsion spring tending to hold the latch in position with the hook 19 in the notch 20. A cotter pin 24 in the plunger engages the web 14 to limit outward movement of the plunger. 80

The detector supporting member includes a lever 25 pivoted as at 26 to the trans- 85 ferrer arm and having one end extended and provided with a lug 27 for engagement with a yielding trip 28. A light tension spring 29 interposed between the lever and the trans- ferrer arm holds said lever in normal position with the lug 27 or some other portion of the lever 25 in contact with the trans- 90 ferrer arm.

The weft detecting element comprises a detector 30 supported by the lever 25 and a tension spring 31 interposed between the detector and the lever 25 holds said detector in normal position relatively to said lever, 95 screw 32 permitting slight adjustment.

Under normal conditions the trans- ferrer arm is brought down on each detecting beat

of the loom so that the detector member is presented to the yarn carried by the bobbin B. When sufficient weft is present the detector is held against sliding movement but when the weft is substantially depleted the detector may slide along the bobbin in engagement with the latch 17 to move the same to the position shown in Fig. 2, thus releasing the plunger and permitting the same to move to the indicating position shown in Fig. 2. The matter thus far described may be substantially the same as that set forth in the aforesaid patent to Ryon, the trip indicated in dotted lines at 28 moving downwardly when an abundant supply of weft is present and remaining in raised position when the detector slides.

My invention relates more particularly to the device for permitting the detector member 30 to have a movement transverse with respect to the carrier lever and in carrying my invention into effect I provide said detector member with a vertical slot 40 slightly longer than but of substantially the same width as the diameter of stud 41 carried in lever 25, so that said detector may have a slight swiveling movement with respect to its support. The lower end of the detector is formed concavely as shown at 42 in Fig. 3.

In order to hold the detector in normal lateral position I provide a light wire spring 43 secured by set screw 44 to a portion of the transferer arm. Said spring is disposed as shown more particularly in Fig. 4 and tends normally to hold the detector in the position shown in Fig. 3, and has no tendency to move the detector to give a false indication.

When the detector is moved downwardly into engagement with the bobbin the latter will be a short distance from front center and will continue to move in the direction indicated by the arrow α in Fig. 3. This movement is permitted by the slotted connection between the detector and its supporting stud 41 and the concave surface 42, being in contact with the convex surface of the bobbin, tends to keep the detector in the same relative position with respect to the bobbin as the latter moves to the dotted line position indicated in Fig. 3. This action is, of course, against the pressure normally exerted by spring 43 but the latter is light and yields without offering much resistance. When the lay is on front center the transferer arm moves upward so that the detector is out of contact with the bobbin and the light spring will restore the detector to its normal transverse position relatively to the transferer arm shown in full lines of Fig. 3.

From the foregoing it will be seen that I have provided means for permitting the detector to remain in the same relative position with respect to the bobbin as the same moves forwardly, thus preventing the bobbin

from rubbing along the under side of the detector. It will further be seen that the detector is capable of a slight transverse movement relatively to its support but that it is normally held yieldingly in one position, i. e. the rearward position with respect to the path followed by the bobbin as the same moves back and forth in the loom.

Having thus described my invention it will be apparent that changes and modifications may be made therein by those skilled in the art without departing from the spirit and scope of the invention, and I do not wish to be limited to the details herein disclosed, but what I claim is:

1. In a weft detecting mechanism for a loom having a supply of weft movable back and forth therein and a transferer arm movable toward the supply of weft in a direction transverse to the movement of the latter, a detector having a loose pivotal connection with respect to the transferer arm, and yielding means to hold said detector normally in a given transverse position with respect to the transferer, said detector being movable transverse of the path of the transferer arm in a direction substantially parallel to the path of the weft, and against the action of said resilient means.

2. In a weft detecting mechanism for a loom having a supply of weft movable back and forth therein and a transferer arm movable toward the supply of weft in a direction transverse to the movement of the latter, a carrier movably mounted on the transferer arm, a detector loosely pivoted to the carrier to have a movement in the direction of the length of the surface to be detected and also to have a slight lateral movement with respect to the transferer arm, and resilient means normally holding said detector in a given transverse position relative to the transferer arm.

3. In a weft detecting mechanism for a loom having a supply of weft movable back and forth therein and a transferer arm movable toward the supply of weft in a direction transverse to the movement of the latter, a weft detector loosely mounted with respect to the transferer arm to have a movement in the direction of the length of the surface to be detected and also a limited movement in the direction in which the weft travels back and forth in the loom, and a concave yarn engaging face for the detector to have engagement with the surface to be detected and assist in moving said detector transversally of the transferer arm.

4. In a weft detecting mechanism for a loom having a supply of weft movable back and forth therein and a transferer arm movable toward the supply of weft in a direction transverse to the movement of the latter, a weft detector loosely mounted with respect to the transferer arm to have a movement in

the direction of the length of the surface to be detected and also a limited movement in the direction in which the weft travels back and forth in the loom, a concave yarn engaging face for the detector to have engagement with the surface to be detected and assist in moving said detector transverse of

the transerrer arm, and resilient means tending to resist transverse movement of the detector relatively to the transerrer arm. ¹⁰

In testimony whereof I have hereunto affixed my signature.

KENNETH J. UNWIN.
